(57) **CLAIM**

The ornamental design for a processing chamber purge plate, as shown and described.

DESCRIPTION

FIG. 1 is a top perspective view of a processing chamber purge plate, showing my new design;

FIG. 2 is a bottom perspective view thereof;

FIG. 3 is a right side view thereof;

FIG. 4 is a left side view thereof;

FIG. 5 is a back view thereof;

FIG. 6 is a front view of thereof;

FIG. 7 is a top view thereof; and,

FIG. 8 is a bottom view thereof.

The even dashed broken lines shown in the drawings represent portions of the processing chamber purge plate that form no part of the claimed design.

1 Claim, 6 Drawing Sheets
